UNITED STATES PATENT OFFICE

105,170

DESIGN FOR A COMBINED PRESSURE REGULATOR AND GAUGE HOLDER

Henry A. Hallum, Seattle, Wash.

Application October 30, 1936, Serial No. 65,608

Term of patent 14 years

To all whom it may concern:

Be it known that I, Henry A. Hallum, a citizen of the United States, residing at Seattle, in the county of King and State of Washington, have invented a new, original, and ornamental Design for a Combined Pressure Regulator and Gauge Holder, of which the following is a specification, reference being had to the accompanying drawing, forming part thereof.

Figure 1 is a front elevation of a combined pressure regulator and gauge holder, showing my new design. Figure 2 is a side elevation of the

same. Figure 3 is a top plan view of the same.

The present design is characterized by its symmetrical appearance, as particularly seen in Figure 1, and by the employment of two upstanding wings forming a gauge holder, one at each side of the position of the pressure gauges, shown in dash lines in Figures 1 and 2.

I claim:

The ornamental design for a combined pressure regulator and gauge holder, substantially as shown and described.

HENRY A. HALLUM.
